US00D603448S

(12) **United States Design Patent**
Markovitz

(10) **Patent No.:** **US D603,448 S**
(45) **Date of Patent:** **** Nov. 3, 2009**

(54) **EYEGLASSES**

(76) Inventor: **Aaron Markovitz**, 123 N. Orchard St.,
Bldg. 6, Ormond Beach, FL (US) 32174

(**) Term: **14 Years**

(21) Appl. No.: **29/293,747**

(22) Filed: **Dec. 10, 2007**

(51) LOC (9) Cl. **16-06**

(52) U.S. Cl. **D16/326**

(58) **Field of Classification Search** D16/101,
D16/300-342; D29/109-110; D24/110.2;

CLAIM

The ornamental design for eyeglasses, as shown and described.

DESCRIPTION

FIG. 1 is a top view illustrating my design for eyeglasses;

FIG. 2 is a perspective view thereof;

FIG. 3 is a side view thereof;

FIG. 4 is a front view thereof;

FIG. 5 is a bottom view thereof; and,

FIG. 6 is a rear view thereof.
